UNITED STATES PATENT OFFICE

ABRAHAM LAZERSON, OF CHICAGO, ILLINOIS, ASSIGNOR TO SOLAR ILLUMINATING COMPANY, OF CHICAGO, ILLINOIS, A CORPORATION OF ILLINOIS

DESIGN FOR A WALL BRACKET FOR LIGHTING FIXTURES

Application filed May 15, 1928. Serial No. 26,681. Term of patent 7 years.

To all whom it may concern:

Be it known that I, ABRAHAM LAZERSON, a citizen of the United States, residing at Chicago, in the county of Cook and State of Illinois, have invented a new, original, and ornamental Design for a Wall Bracket for Lighting Fixtures, of which the following is a specification, reference being had to the accompanying drawing, forming part thereof, in which—

Fig. 1 is a side elevation; and

Fig. 2 is a front elevation, of my improved design, the heavy horizontal lines in the figures indicating the metal strap which holds the glass to the metal back.

I claim:

The ornamental design for a wall bracket for lighting fixtures, substantially as shown.

ABRAHAM LAZERSON.
